UNITED STATES PATENT OFFICE

146,675

DESIGN FOR A MAGNETIC RECORDER OR SIMILAR ARTICLE

Wendfrey C. Nichols, Chicago, Ill., assignor to
Armour Research Foundation, Chicago, Ill., a
corporation of Illinois

Application December 8, 1945, Serial No. 124,509

Term of patent 14 years

(Cl. D26—14)

To all whom it may concern:

Be it known that I, Wendfrey C. Nichols, a citizen of the United States and a resident of the city of Chicago, in the county of Cook and State of Illinois, have invented a new, original, and ornamental Design for a Magnetic Recorder or Similar Article, of which the following is a specification, reference being had to the accompanying drawing, forming a part thereof.

On the drawing:

Figure 1 is an isometric view of the magnetic recorder showing my new design and viewed from a point looking down on the front right corner thereof.

The back and left side of the magnetic recorder, as shown in Figure 2, are substantially plain.

I claim:

The ornamental design for a magnetic recorder or similar article, as shown and described.
WENDFREY C. NICHOLS.
